CLAIM

We claim the ornamental design for a hand blender, as shown and described.

DESCRIPTION

FIG. 1 is a front perspective view of a hand blender of the present invention;

FIG. 2 is a front view thereof;

FIG. 3 is a first side view thereof;

FIG. 4 is a second side view thereof;

FIG. 5 is a rear view thereof;

FIG. 6 is a top view thereof; and,

FIG. 7 is a second side view thereof shown in an alternate position.

The broken lines shown represent unclaimed subject matter and form no part of the claimed design. Additionally, the unevenly broken lines in the drawings define the limits of the claimed design.
